UNITED STATES PATENT OFFICE.

WILLIAM A. KEYS, OF NEW YORK, N. Y.

NECKWEAR.

1,252,450.

Specification of Letters Patent.

Patented Jan. 8, 1918.

Application filed January 9, 1914. Serial No. 811,154.

To all whom it may concern:

Be it known that I, WILLIAM A. KEYS, a citizen of the United States, and a resident of the city, county, and State of New York, 5 have invented certain new and useful Improvements in Neckwear, of which the following is a specification.

My invention relates to improvements in neckwear, and is particularly applicable to 10 neckwear in which the cover fabric, or necktie fabric, is cut on the bias so as to form bias neckwear. It is also addressed to improving the construction, particularly of the tying ends or afts of neckwear, by so 15 constructing the neckwear that any strain put upon the neckwear material in the tying of the tie may be borne by the interlining and not by the cover or necktie fabric. It is also addressed to improving the construction of 20 interlinings for neckwear.

In my improved neckwear I preferably construct or manufacture the neckwear so that when finished the intermediate portion is thinner than the tying ends, thereby 25 facilitating the adjustment of the neckwear when used with two-fold or high-band collars.

In the drawings in which like letters refer to like parts,

30 Figure 1 represents one side of my improved foundation or interlining;

Fig. 2 represents the reverse face of my improved foundation or interlining;

Fig. 3 is a side view of enlarged portions 35 of Figs. 1 and 2;

Fig. 4 represents the interlining and cover fabric in process of assembling the neckwear;

Fig. 5 shows the inner face of my preferred form of neckwear;

Fig. 6 is a cross-section of a tying end during the process of manufacture; and

Fig. 7 is a cross-section of a tying end of the finished tie shown in Fig. 5.

45 The interlining or foundation is composed preferably of three pieces of fabric material. The strip A preferably extends substantially throughout the entire length of the interlining or foundation, and the two 50 strips B—B overlie the strip A, and with it form the interlinings for the tying ends. The strip A is preferably made of material,

cut on the straight, from piece goods, or of a tape. I preferably use muslin or linen or some similar thin and relatively strong fabric. The strips B—B, which are cut, or formed to conform with the shape of the tying ends, are preferably made from soft and relatively thick fabric, such as canton flannel.

60 The strips B—B are placed upon the strip A, and secured thereto by rows of stitching D—D running lengthwise of the interlining, and by rows of stitching C—C running across the interlining at the adjacent ends 65 of the strips B—B. By having the strips B—B fixedly secured throughout their length to the strip A, thereby uniting the plies of the interlining to each other, displacement of the interlining within the tying ends of the tie is obviated, as will be hereafter explained.

65 The cover fabric E, in the ordinary manufacture of neckwear cut on the bias, is cut into two pieces of fabric E—E, and united 70 at the seam as shown in Fig. 4 at F. The interlining having been assembled, as shown in Figs. 1 and 2, and the cover fabric having been formed by the uniting of the two 75 separate pieces, the interlining is placed upon the cover fabric E—E, as shown at the left-hand side of Fig. 4, and is then stitched, preferably by machine, by a row of stitching G which penetrates near the edge of the cover E and the plies A and B of the interlining, thereby fixedly securing the cover 80 fabric to the interlining.

85 In Fig. 4 I have shown this step in the assembling of my improved neckwear by stitching the interlining to one edge of the 90 cover fabric in one end and by stitching it to the opposite edge of the cover fabric in the other tying end. I do not limit myself to this arrangement, as of course, the interlining could be stitched to the same edge of the 95 cover fabric in both ends. The interlining having been stitched to one edge of the cover fabric, the cover fabric is then folded over the edge of the interlining, as shown to the right in Fig. 4, in which the interlining is 100 shown attached to the fold E' of the cover fabric by stitching G, after which the opposite edge E² of the cover fabric is folded on the other edge of the interlining, as shown

in Fig. 6, and the extreme edge E^2 of the cover fabric is then folded upon itself, as shown in Fig. 7, and tacked, stitched as by stitches H or otherwise attached to the 5 fold E' of the cover fabric which, as previously described, is attached to the interlining by the row of stitching G . A necktie put together in this manner possesses, among others, two advantages which are 10 particularly desirable. The first edge of the cover fabric which is attached to the interlining may be so attached by the use of a sewing machine. This provides an extremely secure connection between the interlining and the cover fabric so that all 15 strain which might possibly be put upon the cover fabric will be transmitted to the interlining and the interlining will be extremely efficient in keeping the cover fabric from being 20 stretched or displaced relatively to the interlining. The second advantage derived from this structure is that while one edge of the cover fabric is secured to the interlining by the most effective kind of sewing 25 available, the opposite edge of the cover fabric may be secured to the first mentioned edge of the cover fabric by stitches which, while possibly less effective, are invisible, and at the same time both edges of 30 the cover fabric are securely held to the interlining.

If desired, my improved neckwear may be assembled by folding the cover fabric E on itself, so that the outer faces of the edges 35 E' , E^2 are brought together, placing them upon the interlining and stitching the two edges E' , E^2 to the interlining, and then turning the neckwear so that the interlining would lie on the inside, and the cover fabric 40 would surround same, as shown in Fig. 5. By attaching the folds of the cover fabric to the interlining by a row of stitching G , the interlining is fixedly located within the 45 tying ends of the neckwear, and does not become displaced either in adjusting or in tying the neckwear, as so frequently happens in the ordinary neckwear heretofore in use.

In neckwear constructed as described above, the strain in tying and adjusting is 50 carried by the interlinings or foundation, and not by the cover fabric, as in neckwear heretofore in use. My improvement in neckwear is therefore especially adapted to bias neckwear, as in that form of neckwear, as 55 heretofore constructed, when the strain is borne in part or in whole by the cover fabric, the cover fabric becomes distorted by reason of its being cut on the bias, and the interlinings become displaced with the result that after the neckwear has been in 60 use a short time, it is difficult, if not impossible, to form a suitable knot or bow.

In the preferred form of my invention, which is shown in the drawings, I place a

strip of relatively thin and smooth fabric, 65 such as silk or satin ribbon so that it will form the inner face of an intermediate portion of the neckwear. The said strip I is stitched to the neckband by rows of stitching J — J which pass through all of the plies 70 of the neckband. The ends of this strip I are arranged so that they overlap the adjacent ends of the interlining of the strips B—B, and the stitching J also passes through, not only the strip I, but the cover 75 fabric E and the foundation or interlining strips A and B—B. When this strip I is used, part or all of the material of the cover E under the strip I may be removed, if desired. 80

I preferably assemble my neckwear, described above, so that the strip A of the foundation or interlining lies adjacent to the folds of the cover fabric E of the inner side of the neckwear, and the strips B—B of the interlining or foundation come in contact with the inside of the outer face of the neckwear. The canton flannel, which I preferably use for the strips B—B, is softer than the muslin or linen strip A, and affords a 90 surface which adheres more readily to the inside of the cover material than would the linen or muslin strip A. 95

By the use of my improved foundation or interlining, I have found that it is a comparatively easy matter to stitch the bias material of the cover proper to the material, cut on the straight, of the interlining.

I claim—

1. In a necktie comprising tying ends and an intermediate portion, an interlining and a cover therefor, said interlining composed of a relatively thin strip of material extending substantially throughout the length of the interlining, a relatively soft and thick fabric overlapping and attached to the said strip and adapted to lie within a tying end of the necktie, the cover fabric of said tying ends being folded completely to inclose the tying ends of the interlining, one of said folds being stitched to the said interlining substantially throughout the length of a tying end, the other fold being secured to the aforesaid fold of the cover fabric by an independent row of stitches, a strip of material placed on the inner face of the neckband so that one of its ends overlaps the plurality of plies of material forming the interlining for the tying ends and stitches engaging with said strip on the 110 neckband and with said interlining. 115

2. In a necktie comprising tying ends and an intermediate portion, an interlining and a cover therefor, said interlining being composed of a strip of material extending substantially throughout a tying end and said intermediate portion of the tie, the cover fabric of said tying end being folded com- 120 125

pletely to inclose said tying end of the interlining, one of said folds being stitched to said interlining substantially throughout the length of said tying end, the other fold being secured to the aforesaid fold of the cover fabric by an independent row of stitches.

In testimony whereof, I have signed my name to this specification, in the presence of two subscribing witnesses.

WILLIAM A. KEYS.
